UNITED STATES PATENT OFFICE

ARTHUR H. DU GRENIER, OF HAVERHILL, MASSACHUSETTS

DISPENSING MECHANISM

Application filed February 10, 1932. Serial No. 592,027.

This invention relates to certain improvements in coin released dispensing machines of the "selective" type, and particularly of the type disclosed in my prior Patent No.

5 1,821,501, dated September 1, 1931, in which an endless chain is provided with a series of article holding compartments formed by a series of shelves, which project perpendicularly from the links of the chain on which 10 they are mounted, the arrangement being such that the chain may be driven step by step in one direction by an operating lever, to enable the compartments to be successively moved into a position for inspection 15 through a suitably arranged window, so that if a suitable coin is then placed in the machine and the lever is again operated, the article selected will be delivered.

In machines of this character, prior to my 20 invention, so far as I am aware the shelves have been spaced to correspond to the length of the links of the chain, so that all the compartments are of the same width. While this arrangement is desirably in dispensing 25 packages of uniform size, as packages of cigarettes, when a machine of this type is employed for dispensing a variety of packages, as bars of candy, this arrangement is not satisfactory, for the reason that packages of different varieties of candy, which ordinarily 30 sell, for example, for five cents, vary widely in width, or thickness, although in length the variation is usually comparatively small. In consequence, any series of compartments 35 of uniform width will be much too wide for some packages and not sufficiently wide for others, so that the space in some of the compartments will be only partly occupied, and, in consequence, a part of the space will be 40 wasted, while other packages which are sold for the same price cannot be vended from the machine at all.

Also, in practical operation of machines 45 substantially identical to that disclosed in any said patent, the wrappers of the packages dispensed were sometimes torn when carried beneath the lower sprocket without being dispensed, at which time they usually rest on the supporting door, and I have ascertained that as the package was pushed

along by the shelf on the carrier, it was sometimes caught between the end of the shelf and the door, with resulting damage to the wrapper.

The objects of my invention are to provide 55 a form of article holding endless chain for machines similar to that disclosed in my said prior patent, in which the distances between the article holding shelves on the chain may be varied according to the width, or thickness of the various packages which are to be placed thereon, so that a large assortment of candy bars, or the like, all of which sell for a uniform price, but vary in size, may be vended from the machine, and practically all 60 of the space on the chain, which is available for storage and subsequent vending purposes, may be utilized, so that packages of substantially both greater and less width, or thickness than the length of the chain links may 65 be dispensed.

A further object of my invention is so to construct the carrier, that the packages will not be likely to be damaged by the action of the carrier shelves in pushing the packages 70 along on the dispensing door.

I accomplish these objects primarily by providing an endless chain having a series of compartments each of which comprises a bottom and two parallel sides held in fixed 75 relation therewith and arranging said compartments in pairs, so that the opposite sides of each pair of compartments are spaced at distances equal to the length of two links of the chain, while the adjacent sides of the pair of compartments are located side by side in different positions between the outer sides, so that the total widths of the two compartments of each pair is always the same but the 80 relative widths thereof are varied according to requirements.

Also by arranging the sides of each compartment with respect to the link pivot on which it swings as it passes beneath the bottom sprocket, so that the side which pushes the package along on the dispensing door will be held at an acute angle to a radial position with respect to the axis about which it is carried, causing the package to tend to 85 90 95 100

slide up on the side, so that it will not be caught beneath its edge.

For a more complete disclosure of the invention, reference is now made to the following specification in connection with the accompanying drawing in which:

Fig. 1 is a side elevation of the carrier actuating mechanism.

Fig. 2 is a side elevation of the lower portion of the dispensing mechanism viewed from the left hand side.

Figs. 3 and 4 are left side and front views respectively of a portion of the carrier.

Fig. 5 is a detail view in perspective of one of the carrier compartments.

As the carrier herein shown and described is primarily intended to be employed in a dispensing machine such as is disclosed in my said prior patent, only such parts are shown, as are directly associated with the parts embodying the invention herein claimed.

In the drawing 1 indicates the front side of the casing, within which the various parts of the machine are enclosed, and 2 an inspection window therein, in front of which the packages, to be dispensed are successively displayed.

The lower sprockets 3 of the carrier 4, only one of which is shown, are mounted on a shaft 5, and the means employed for driving the carrier, so that the compartments are successively presented in front of the window 2 is essentially the same as that of my said patent, said means comprising a manually operable lever 6, of angular form, which is pivoted at 7 and is engaged with a reciprocally mounted actuator 8, which is arranged to engage a wheel 9 mounted on the shaft 5 thru a pawl 10, the arrangement being such that when the lever is depressed to its lowest point the wheel 9 will be rotated thru 90°, so that the sprocket 3 will be rotated correspondingly and the carrier will be moved a distance equal to the length of one link of the chain, and will come to rest in the position of Fig. 2. The dispensing door 12 is hinged at 13 to the casing and extends beneath the lower sprocket 3 of the carrier, to support the packages in the carrier as they pass beneath the sprocket, when not released, and to swing downward, when released upon the insertion of a suitable coin, and to permit a package in the carrier compartment which is being carried beneath the sprocket, to fall therefrom and be delivered, as described in said patent.

The carrier is similar to that described in said patent, in that it comprises a series of links connected by pivot pins 14, each pair of links having an article receiving compartment mounted thereon which comprises a bottom and two sides which are perpendicular thereto. As each compartment which comprises a section of the chain differs there-

from specifically, it will now be described in detail.

As best shown in Fig. 5, each section comprises a bottom a , sides b and c , which extend perpendicularly therefrom, and ears d at each end of the bottom, which form a pair of links of the chain, each ear having two pivot holes e and f therein, which are spaced to equal the length of a link and which are adapted to receive the connecting pivot pins 14, said pins projecting at each side of the chain in position to engage the four notches in the bottom sprockets, and also in the top sprockets not shown. As thus connected the adjacent sides of adjacent sections are held practically in contact when the chain is drawn straight.

According to my invention, the chain comprises a series of pairs of sections, all of which are the same in length, but in respect to which the sections of each pair vary from each other and from other sections in the following particulars. For example, the two sections having ears d' and d'' are provided with bottoms a' , a'' which are of different width, the bottom a' being of substantially less width than the bottom a'' , so that while the distance from the side of b' to the side c'' is equal to twice the distance between the pivot holes e and f , of any one section, the distance between the sides b' and b'' is substantially less than the distance between the sides c' and c'' , so that a relatively thin package, as x , will occupy nearly all the space between the sides b' , c' and a relatively thick package, as y , will occupy all the space between the sides b'' , c'' . Similarly the bottom a'' is of less width than the bottom a' and the bottom a'' is of greater width than the bottom a' , but the total widths of the bottoms a' and a'' is equal to the total widths of the bottoms a'' and a' , so that the distances between the opposite sides of each pair of sections is the same, while the distance between the sides of each section is, or may be different from that between the sides of the other sections. In other words the two adjacent sides of any pair may be located at any point between the opposite sides of the pair, but each section of a pair is the complement of the other section of the pair, so far as the width of the space between its sides is concerned, although the formation of the ears d of all the sections is identical.

In practice, therefore, a large variety of sizes of compartments within certain limits may be provided, so that a number of compartments of a width corresponding to the width or thickness of any candy package, or bar which is on the market, within certain limits, may be provided, thereby enabling each compartment of the carrier to be completely filled, leaving no more waste space than is necessary to permit the free delivery of the package and permitting the dispensing

of many packages of greater width or thickness than the length of each individual link of the chain.

While in practice some of the compartments may be equal in width to the length of the links, if the chain comprises an odd number of compartments, the odd compartment must be equal in width to the length of the link, while the others may be varied according to requirements.

So far as the actual dispensing operation is concerned, it is the same as disclosed in my said patent, as each package in the compartments will be successively held in front of the inspection window and then will be moved down to the position in which it will fall from the compartment provided the door has been released.

In order, however, that only one package at a time will be displayed at the inspection window, the window is so located and the operating mechanism is so timed in relation thereto that before a compartment reaches the position for inspection, shown in Figs. 1 and 2, the lower pivot of the link, as d^2 , on which the compartment is mounted, is carried so far below the horizontal line through the axis of the sprocket 3 that the link will be swung rearward from the vertical line of the axes of the pivots above it, causing the sides b^3 c^3 thereof to be swung away from the next compartment above, which will still be held in the position in which its sides are horizontal. In consequence the sides of the compartment will be tilted downward so that the outer ends of its sides will be held at a substantial distance from the next compartment above by the time the compartment is brought to rest in the inspection position.

In case the package is thin or narrow, as in Fig. 2, it will usually be held about midway of the inspection window, while if it is relatively wide or thick, a small portion of the package may not be held in a position in which it can be seen through the window, but a sufficient portion thereof may be seen to enable the purchaser to identify it.

A variety of candy bars, or the like, may thus be dispensed from a single machine and a sufficient number may be placed therein at one time to avoid undesirably frequent replenishments.

When the carrier is driven forward, and the door 12 is held in closed position, the rear side of each section, or compartment pushes along the package therein while supported on the door, and with the construction of my said patent, the wrapper of the package was sometimes damaged. According to the construction and arrangement disclosed in said patent, the pivotal points of the links of each section were so arranged, with relation to the position of the sides, that the rear pivotal point of each link, considered with relation to the direction in which the carrier was

driven, was in the rear of the rear side of the section.

Consequently, when both pivots of the section were engaged with the lower sprocket, the rear side of the section was held in a position approximately corresponding to a radius from the center of the sprocket, so that the side which pushed the package along on the door was held in a position nearly perpendicular to the door, and, as a result, there was a tendency for the wrapper to become caught between the edge of the side and the door.

I have ascertained that this difficulty may be almost entirely avoided by arranging both pivots of each section in advance of the rear side thereof, or of the side which pushes the package over the door, so that each package-propelling side extends at a substantial angle of divergence from a point where a radial line from the center of the sprocket meets the side in the top surface of the door, as illustrated by the positions of the sides b^3 , b^4 with relation to the radial lines o , o' in Fig. 2. In this position of the sides with relation to the package, it will be apparent that, as a side acts to push along the package on the door, the package will tend to slide, or be deflected up on the side, so that there will be little, or no tendency for the wrapper of the package to be caught between the door and the edge of the side and much less tendency than if the side were held in an approximately radial position with respect to the curved surface of the door, as disclosed in my said prior patent.

I claim:

1. In a dispensing carrier of the type described, a series of pivotally connected links, of equal length, a series of pairs of article holding compartments each mounted on two adjacent links, each compartment of a pair being of different width, and the combined widths of each pair of compartments corresponding to the combined lengths of two of the links.

2. In a dispensing carrier of the type described, a series of pivotally connected links of equal length, each having a pair of supports projecting therefrom and providing an article receiving compartment therebetween, the distance between the supports of each link being substantially varied from that between the supports of other links, to provide the carrier with compartments of varying widths, and the total width of each successive pair of adjacent compartments being approximately the same.

3. In a dispensing carrier of the type described, a series of pairs of pivotally connected links of equal length, a pair of shelves projecting perpendicularly from each link, each shelf being arranged to be held in proximity to the adjacent shelf of the next adjacent link, the opposite shelves of each pair

of links being spaced at equal distances and the adjacent shelves between each pair of opposite shelves being located in varying positions therebetween, to provide article receiving compartments of different widths.

4. In a dispensing machine of the type described, comprising a carrier having a series of pivotally connected links, each link having a pair of shelves projecting perpendicularly therefrom to provide an article receiving compartment therebetween, a lower sprocket about which the carrier is driven, whereby the shelves of each link will be held in a depending position when the link is held in a position beneath the sprocket to permit delivery of an article contained in the compartment thereof, a door normally disposed beneath said sprocket having its top surface concentric with the axis of the sprocket, to provide a support for the article in each compartment when held beneath the sprocket, whereby the rearmost shelf of each link may propel the article in the compartment thereof over the door while supported thereby, the rearmost pivot of each link being arranged in advance of the rearmost side thereof, so that said side will be held in a position in which it diverges from a radial position with relation to the surface of the door as it extends therefrom to the link.

In testimony whereof, I have signed my name to this specification.

ARTHUR H. DU GRENIER.
